UNITED STATES PATENT OFFICE.

HORACE B. SWARTZWELDER, OF LANCASTER, PENNSYLVANIA.

CUPBOARD-CATCH.

SPECIFICATION forming part of Letters Patent No. 349,671, dated September 21, 1886.

Application filed April 17, 1886. Serial No. 199,174. (No model.)

To all whom it may concern:

Be it known that I, HORACE B. SWARTZWELDER, a citizen of the United States, residing at Lancaster, in the county of Lancaster 5 and State of Pennsylvania, have invented certain new and useful Improvements in Cupboard-Catches; and I do hereby declare the following to be a full, clear, and exact description of the invention, such as will enable others skilled in the art to which it appertains to make and use the same.

My improvements pertain to what is known to the trade as "spring" cupboard-catches, and can be used under all circumstances where 15 catches of this class are at present in service; and the object of my improvement is to furnish an automatic catch which shall be compact and simple, with a knob which shall serve the double purpose of a handle with which to 20 open the door, and at the same time a suitable case or covering for the working parts of this device to protect the same from accident, and as it is necessary to know the arrangement of this device in order to open the door, 25 it will thereby avoid the annoyance of young children and others who do not know it from working the same—a convenience which will be appreciated by all housewives.

The nature and operation of this device will 30 be readily seen by all conversant with such matters from the following explanations and the accompanying drawings.

Figure 1 represents a full side sectional elevation showing all the working parts of this 35 device; Fig. 2, a full side perspective view of the body of this arrangement; Fig. 3, a perspective front elevation showing the knob fast to the door.

Similar letters refer to similar parts throughout the several views.

The knob A is held fast to the door by means of the screws n n. The lever d, which is journaled in the recess of the knob at C, projects through the door, so that the offset e on its end 45 will clutch fast with the shelf-catch f, which is made fast to the bottom of the shelf with screws,

as shown. The piston or push-button a, working the recess h of the knob, is journaled fast to the lever d at b, and the end of the lever d is kept in contact with the shelf-catch f by means 50 of the spiral spring m, which also keeps the other end in contact with a projection in the recess of the knob at g.

Having thus described this device, the manner of working it is as follows: When the door is shut and locked, as shown in Fig. 1, to open it, place the front and second fingers of the hand in the recess of the knob A, Fig. 2, and force in the push-button or piston a with the thumb. Now, as will be seen by reference to 60 Fig. 1, as the journal b is eccentrically out of line with the journal C, the action of forcing in the button a will drive the jaw e on the end of the lever d down and out of clutch with the shelf-catch f, thereby allowing the door to 55 swing open. When the thumb is removed from the button the spring m will force the lever back and the button out until the upper end of the lever d comes in contact with the projection g in the recess of the knob, which always keeps the lever in proper position.

To close the door it is only necessary to push it shut, for, as the device is automatic, it locks itself.

Having thus described my invention, what 75 I claim as new, and desire to secure by Letters Patent, is—

The recessed knob A, in combination with lever d, which is provided with offset e, and pivoted within said knob at c, the catch f, 80 which engages said offset, the spring m, which maintains said lever in such engagement, and the push-button a, which is pivoted to the inner end of said lever at a point out of line with said pivot c, substantially as and for the purpose set forth.

In testimony whereof I affix my signature in presence of two witnesses.

HORACE B. SWARTZWELDER.

Witnesses:

A. F. SHENCK,

W.M. J. MINGLE.
